UNITED STATES PATENT OFFICE.

AUGUST SUNDH, OF YONKERS, NEW YORK, ASSIGNOR TO OTIS ELEVATOR COMPANY,
OF JERSEY CITY, NEW JERSEY, A CORPORATION OF NEW JERSEY.

COMPOUND BRAKE FOR TRACTION-ELEVATORS.

1,043,740.

Specification of Letters Patent.

Patented Nov. 5, 1912.

Application filed June 24, 1907. Serial No. 380,426.

To all whom it may concern:

Be it known that I, AUGUST SUNDH, a citizen of the United States, residing at Yonkers, in the county of Westchester and State 5 of New York, have invented a new and useful Improvement in Compound Brakes for Traction-Elevators, of which the following is a specification.

My invention relates to compound brakes 10 for elevators and one of its objects is to provide simple and efficient means for braking an elevator upon stopping, and it consists in the novel construction and arrangement of parts hereinafter described and specifically 15 pointed out in the appended claims.

The accompanying drawing illustrate my invention applied to a direct or traction drive elevator system, to which it is particularly well adapted.

Figure 1 shows one application of my invention; Fig. 2 a modification thereof; and Figs. 3 and 4 are views of details.

Referring to the drawing, C designates an elevator car suspended from an overhead 25 sheave 21 by means of cables 1 which pass down and around a friction driving sheave 30, thence up and over a sheave 4 and leading down and connected to a counterbalance weight 2. The driving sheave 30 is mounted 30 to rotate with the motor shaft 46 and adapted to be revolved by the motor M in either direction, according to whether the car is to be lifted or lowered. Preferably the inner periphery of the driving sheave 30 is turned 35 to a smooth surface adapted to be engaged by suitable brake shoes. The brake device which operates on this inner periphery comprises a frame 47 loosely mounted on the motor shaft 46 and has two outwardly extending arms 45 and 44. The lower part of the frame 47 is provided with a recessed portion adapted to receive a magnet winding 37 and magnet core 38. The lower end of the core 38 is connected at 48 to the toggle links 35 and 36 which in turn are connected 40 to brake levers 33 and 34, respectively. The brake levers are pivoted to the outwardly extending arms 45 and 44 at 40 and 41, respectively, and each brake lever carries a 45 brake shoe 31 and 32 pivoted at 50 and 51, respectively, and adapted to engage the smooth inner periphery of the driving sheave 30.

Fastened to the brake frame at 42 and 43, 50 and substantially equally distant from the

motor shaft 46, are cables 27 and 28, respectively, which are connected by the thimble 26 to a single cable 23 which passes around a direction pulley 24 mounted on fixed brackets 25 and up to the top of the hatchway 60 where it is fastened to one end of a brake lever 7. The other end of this lever is pivoted at 6 to an extension of the sheave bearing 5, or to any other fixed support. This lever 7 is part of a brake device comprising 65 toggle links 11 and 12 which are connected together at 10 to a link 9 which is connected to the brake lever 7 by a pin 8. The toggle links 11 and 12 are connected to brake shoes 19 and 20 at 17 and 18, respectively. Additional links 13 and 14 are attached at 17 and 18 to the brake shoes 19 and 20 and are pivoted at 15 and 16, respectively, to the fixed overhead beams 3. The brake shoes 19 and 20 may be arranged to bear against the 70 periphery of the sheaves 4 and 21 as shown, or to bear directly against the cables 1, in which case it would be necessary to slightly modify the form of the brake shoes, or the 75 brake shoes 19 and 20 may engage both the cable and the peripheries of the overhead sheaves. See Fig. 4.

The brake device mounted on the motor shaft is applied by means of a compression spring 39 which forces the magnet core 38 80 and toggle links 35 and 36 downwardly, thereby moving the brake levers 33 and 34 outwardly and thus forcing the brake shoes 31 and 32 against the inner periphery of the driving sheave 30. In order to release the 85 brake shoes from the driving sheave, the magnet coil 37 is energized and the magnet core 38 is lifted, overcoming the action of the spring 39 and causing the toggle links 35 and 36 to draw the brake levers 33 and 34 90 inwardly and thereby release the brake shoes 31 and 32 from engagement with the inner periphery of the driving sheave 30. The overhead brake device also is provided with a compression spring 49, one end of which 95 rests on a fixed support or the beam 3; the other end, by pressing against an abutment piece 52 connected to the pin 10, lifts the toggle links 11 and 12, thereby lifting the right-hand end of the brake lever 7 and withdrawing the brake shoes 19 and 20 from their 100 respective sheaves. The upward movement of the lever arm 7 is limited by the cables 23, 27 and 28. The tendency of the spring 39 is to apply the brake shoes 31, 32 to the 105 110

driving sheave 30, while the tendency of the spring 49 is to release the brake shoes 19 and 20 from the sheaves 4 and 21 and those portions of the cables 1 opposite the latter & brake shoes.

I will now point out the operation of the brake device just described.

Assuming the motor to be revolving in a clockwise direction corresponding to an upward movement of the car and that the magnet 37 is fully energized to release the driving sheave brake shoes and the spring 49 has acted to release the overhead brake shoes 19 and 20, the elevator will run freely. In order to bring the car to rest current is cut off from the motor and the brake solenoid 37, and the latter is at once deenergized and allows the spring 39 to apply the brake shoes to the driving sheave 30 as before pointed out. The tendency of the driving sheave 30 is to continue to revolve owing to the momentum of the moving parts throughout the system, and the motor brake device also tends to revolve, due to the frictional contact existing between its brake shoes and the driving sheave 30. Such being the case, as the motor brake device together with the driving sheave 30 tend to revolve in a clockwise direction, a downward pull will be exerted upon the right-hand end of brake lever 7 through the cables 28 and 23. This downward pull upon the lever 7 will be transmitted to the toggle links 11 and 12, thereby overcoming the upward pressure of the spring 49 and forcing the brake shoes 19 and 20 against the respective cable sheaves 4 and 21. The downward movement of the brake lever 7 is arrested as soon as the overhead brakes are firmly applied to their respective sheaves, and the motor brake device is therefore prevented from further movement by the cables 23 and 28. It is clearly seen that the combined retarding action of the brakes, one acting primarily and directly on the motor; the other acting secondarily on the overhead cable sheaves, produce a powerful braking action, and, moreover, this braking effect is proportional to the speed and momentum of the moving elevator upon stopping. This is a valuable feature since it makes it possible to stop an elevator car with varying loads at any desired point in its travel with greater accuracy than when employing brake apparatus for the motor alone.

In order to release the brakes to allow the elevator to start a circuit is closed to the brake magnet 37, and the same is energized to withdraw the brake shoes operated thereby. The motor brake device is now free to move about the shaft 46 and the spring 49 at once lifts the toggle links 11 and 12, thereby releasing the connected brake shoes from their respective cable sheaves and lifting the lever 7. This effects an up-

ward pull upon the cables 23 and 28 and the result will be to restore the motor brake device to its original central position as shown on the drawing. The motor and its connected elevator car and counterweight are now free to start again to lift or lower the car, since both brake devices are released.

Should the brakes be applied to stop the elevator when the car is descending, the motor brake device together with the driving sheave 30 will move in a counter-clockwise direction and a pull will be exerted upon the cable 27 instead of the cable 28 as before described in connection with an ascending elevator car. The subsequent operation of both brakes will be the same as before pointed out and needs no further description. The pressure of the brake shoes 31 and 32 against the inner periphery of the driving sheave 30 may be varied at will by adjusting the tension of the spring 39, and the pressure of the brake shoes 19 and 20 against the respective cable sheaves associated therewith may be varied by adjusting the tension of the spring 49. I sometimes provide a limit stop 53 for the brake lever 7, in which case the overhead brakes and the motor brakes are always applied with uniform strength, and instead of using the cables 27 and 28 the cable 23 may be made long enough to be connected directly to the brake frame 47 at a point directly in line with the motor shaft as shown in Fig. 2 so that no matter which way the brake frame is revolved about the motor shaft a pull will be exerted upon the cable 23 and so transmitted to the overhead brakes. The combined action of the motor and overhead brakes effectually overcomes any slipping of the cables on a traction or direct drive elevator, at the same time the uniform and successive application of both sets of brakes produces a much larger friction capacity than if either brake alone acted; also, while the braking effect is vastly increased no extra tension is placed upon the hoisting cables.

It should be particularly noted that braking action in the traction elevator system illustrated is distributed, a primary braking action being produced at the driving sheave and a secondary braking action on the overhead sheaves and the power transmitting cables. The application of a braking action on the overhead sheaves and the cables associated therewith, moreover, tends to prevent stretching of the ropes and consequent teetering or jumping of the car. It will also be seen that tendency of the cables to slip on the driving sheaves is counteracted by secondary braking action.

Instead of a plurality of braking shoes operated by a single lever to apply brakes to corresponding direction sheaves, there may be only one shoe associated with a

single pulley, particularly in elevator systems other than of the type illustrated. Furthermore, there may be a plurality of levers like that designated by the reference number 7, each connected to a brake for a rotating sheave and each operated from the primary braking apparatus which is pivoted as a whole loosely on the motor shaft or on an axis substantially in alignment or co-incident therewith.

Obviously those skilled in the art may make various changes in the details and arrangement of parts without departing from the spirit and scope of my invention, and I desire therefore not to be limited to the precise construction herein disclosed.

What I claim and desire to have protected by Letters Patent of the United States is:—

1. In a traction elevator, the combination with a motor, a drive pulley thereon, a car, a direction sheave between the car and motor pulley, a cable connected to the car, passing over the direction pulley and frictionally engaging the drive pulley, of a brake for the drive pulley, a brake for the direction pulley, and operative connections between the brakes.

2. In a traction elevator, a motor, a motor drive pulley, a car, a cable connected to the car and extending to the drive pulley, a pulley between said drive pulley and the car, with which the cable engages, a brake for each of said pulleys, means for applying one of the brakes, and operating connections between the brakes.

3. In a traction elevator, a motor, a motor drive pulley, a car, a cable connected to the car, and extending to the drive pulley, a pulley between said drive pulley and the car, with which the cable engages, a brake for each of said pulleys, and means operative upon the application of one brake to apply the other brake.

4. In a traction elevator, a motor, a motor drive pulley, a car, a cable connected to the car and in engagement with the drive pulley, a pulley with which the cable engages between the drive pulley and the car, a brake for each pulley, and connections between said brakes operative upon the application of the motor brake to apply the other brake.

5. In a traction elevator, a motor, a motor drive pulley, a car, a cable connected to the car and in engagement with the drive pulley, a pulley with which the cable engages between the drive pulley and the car, a brake pivoted for movement about the axis of the drive pulley, a brake for the other pulley, a movable member connected to the last-named brake to operate it, and means connecting said member and the motor brake to operate said member when the motor brake is applied.

6. In a traction elevator, the combination

of a motor, a motor pulley, overhead sheaves, a car, a counterweight, a cable passing over said sheaves, around the motor pulley and connected to the car and counterweight, a brake for the motor pulley, brakes for the overhead sheaves, and means controlled by the motor brake for applying the overhead brakes when the motor brake is applied.

7. In a traction elevator, the combination of a motor, a motor pulley, overhead sheaves, a car, a counterweight, a cable passing over said sheaves, around the motor pulley and connected to the car and counterweight, a brake for the motor pulley, brakes for the overhead sheaves, a lever connected to said last named brakes and movable into position to apply the brakes, and means connecting the lever and motor brake to operate the lever and apply the overhead brakes when the motor brake is applied.

8. The combination of a plurality of sheaves, a cable engaging said sheaves, a brake for each sheave, means to apply one of said brakes, and mechanical operating means between said brake and the other brake or brakes to apply all of said brakes by power supplied from the first brake.

9. The combination of a sheave, a brake pivoted concentrically with the sheave and having a brake shoe movable into engagement with the sheave, a second sheave, a cable extending between and engaging the sheaves, a lever, a brake shoe connected to the lever in position to engage said second sheave when the lever is operated, and a connection between the lever and the first brake, movable with said first brake to operate the lever and apply the second brake.

10. In an elevator, the combination of a motor operable in either direction, a drive pulley thereon, a car, a cable supporting said car and running on said drive pulley, a sheave between the car and drive pulley over which said cable passes, a brake for the drive pulley movable with the pulley in either direction when the brake is applied, a second brake in position to engage the sheave, a connection between said brakes, operative upon the application of the first brake to apply the second brake and limiting the movement of the first brake.

11. The combination of a drive pulley, a brake pivoted for movement about the axis of the drive pulley and having a brake shoe movable into frictional engagement with the pulley, a cable in running contact with and operated by said pulley, a brake for said cable, and operating connections between said brakes movable to apply the second brake when the first brake is applied and moved about its axis by the frictional engagement between its shoe and the drive pulley.

12. In an elevator, the combination of a motor, a drive pulley thereon, a brake pivoted on the shaft of the motor and having shoes positioned to engage the internal periphery of the drive pulley, a car, an overhead pulley, a cable connected to the car, passing over the overhead pulley and in engagement with the drive pulley, a brake for the overhead pulley, an operating lever for the brake, a flexible connection extending from said lever to the motor brake and connected thereto at points on opposite sides of the axis of the brake.
13. In an elevator, the combination with a motor operable in either direction, a car, a motor drive pulley, an overhead pulley, a cable connected to the car extending over said pulley and in frictional engagement with the motor drive pulley, of a brake pivoted on the motor shaft, a brake for the overhead pulley, an operating arm for said last named brake, a direction pulley, a cable connected to the operating arm and passing about the direction pulley, and means connecting said last named cable to the motor brake at points on opposite sides of the motor shaft.
14. In an elevator, the combination of a motor operable in either direction, a motor drive pulley, a car, a counterweight, overhead pulleys, a cable connected at one end to the car, passing over one of the overhead pulleys, extending downward around the drive pulley, upward around the other overhead pulley and connected at its other end to the counterweight, a brake pivoted on the motor shaft and having brake shoes
- in position to engage the inner periphery of the drive pulley, brake shoes between the overhead pulleys and movable into engagement therewith, toggle links connecting said brake shoes, an operating lever connected to the toggle links and movable into position to apply the brake shoes, a cable connected to the operating lever, a direction pulley about which the cable extends, and connections from the cable to the motor brake at points on opposite sides of the motor shaft.
15. In an elevator, the combination with a car, a cable, pulleys over which the cable passes and means for driving one of said pulleys, of a brake pivoted for movement about the axis of one of the pulleys and having a brake shoe movable into frictional engagement with the pulley to give a turning pull to the brake varying with the pressure of the brake shoe on the pulley, a second brake in operative relation to another of the pulleys, a member connected to the second brake and movable into position to apply the brake, and a connection between said member and the first brake for applying the second brake with a power proportional to the power with which the first brake is applied.

In testimony whereof, I have signed my name to this specification in the presence of two subscribing witnesses.

AUGUST SUNDH.
